UNITED STATES PATENT OFFICE.

LEWIS M. HULL, OF BOONTON, NEW JERSEY, ASSIGNOR TO RADIO FREQUENCY LABORATORIES, INCORPORATED, OF BOONTON, NEW JERSEY, A CORPORATION OF NEW JERSEY.

ELECTRICAL AMPLIFIER CIRCUIT.

Application filed August 24, 1927. Serial No. 215,189.

This invention relates to electrical amplifier circuits of the type adapted for use in connection with a vacuum tube. Such a vacuum tube may include an emitting cathode, an anode, and one or more additional elements having the form of grids or the like. The invention relates especially to a balanced amplifier circuit of the foregoing type which is especially suited for use in a radio receiving set, and which provides means for reducing or eliminating retroaction or regeneration from the output or plate circuit of the amplifier stage into the input or grid circuit thereof. Such retroaction may be caused by coupling due to capacities between the elements of the vacuum tube and their associated connections, and especially by coupling due to the natural capacity between the anode and control element or grid of the vacuum tube.

Figure 1 shows a single amplifier stage embodying my invention. Figure 2 shows an amplifier stage employing a double grid vacuum tube and embodying my invention.

Referring to Figure 1, which shows a preferred embodiment of my invention, the input circuit of the amplifier stage may assume any desired form, and is here represented as being constituted by the tuned circuit $L_o - C_o$. One terminal of the input circuit is connected to the control electrode or grid G. The other terminal is connected to the cathode F, which may be any emitting structure, suitably a filament heated by current from the battery A or from an alternating current source. My invention applies equally, of course, to vacuum tubes having cathodes heated by means of alternating current, in which case a centre tap or other conventional arrangement may be employed. A natural capacity exists between the control element G and the anode or plate P and their associated connections, and this capacity may be represented by the dotted lines at C_m . The plate coil is shown at L_1 , and may form the primary of an output transformer $L_1 - L_2$, of which the secondary may suitably be tuned by means of the condenser C_2 . Connected in series with the plate coil L_1 between anode P and cathode F, and coupled thereto, is a balancing coil L_3 . The coils L_1 and L_3 may be coupled together with any desired degree of coupling up to and including close or substantially

unity coupling. In certain physical embodiments of my invention which I have built and operated, I have found that close or substantially unity coupling may be advantageously employed. The invention is not limited thereto, however, since circuits embodying my invention operate successfully, I have found, when the coupling employed is substantially less than unity coupling or its equivalent. Any suitable source of space current, for example a B-battery, B, may be included in series with the coils L_1 and L_3 , and may be by-passed by condenser C' as shown. Between the control electrode or grid G and the junction point of coils L_1 and L_3 is connected a balancing condenser C_1 , which may suitably be adjusted to the proper value when the amplifier is built, and will probably require no adjustment thereafter. A C-battery may be employed for biasing the grid, if desired.

The coils L_1 and L_3 are of course coupled and connected in the proper sense, as shown, so that currents flowing through the balancing capacity C_1 reduce or substantially balance out undesired currents flowing through the capacity C_m or other natural capacities of the system. A principal balance condition, when the coils L_1 and L_3 are coupled in this sense, may be approximately expressed as follows:

$$\frac{C_m}{C_1} = \frac{M_{32}}{M_{12} - M_{32}}$$

where the several mutual inductances are as indicated in the drawing. A subsidiary balance condition, which does not require exact fulfillment in order to obtain good operation, is:

$$\frac{C_m}{C_1} = \frac{M_{13} - L_3}{L_p}$$

where L_p is the total plate inductance, i. e.,

$$L_p = L_1 + L_3 - M_{13}$$

These balance conditions may be more or less fulfilled depending upon the degree of balance which is required and the amount of regeneration which is permitted; and it must be understood that the invention is not dependent upon the correctness of these mathematical conditions.

An arrangement employing a vacuum tube of the double grid type is shown in Figure

2, the inner grid G_1 being employed as control element, and the outer grid G_2 being given a positive bias. This may be done by means of a connection to the "B"-battery 5 as shown (by-pass condensers C' being used if necessary), or by means of a separate battery, or connection to a socket-power device, or otherwise. The foregoing connection of the grids G_1 and G_2 may be reversed in cer- 10 tain cases.

Any number of amplifier stages similar to those shown in Fig. 1 or in Fig. 2 may be cascaded together if desired, or such stages may be cascaded with unbalanced or un- 15 tuned stages, in a well recognized manner. A preceding stage may suitably be coupled through coil L to the coil L_0 of the tuned circuit L_0-C_0 ; a succeeding stage may suitably be connected to the terminals 1 and 2, 20 as by connecting these terminals to the control element and cathode, respectively, of the next tube. According to a preferred embodiment of the invention, therefore, each amplifier circuit or stage is provided with 25 an input transformer $L-L_0$ and an output transformer L_1-L_2 , as described above and shown in the accompanying drawings. Other methods of cascading the stages are 30 of course applicable to this circuit, however, which may be arranged accordingly. Other variations and modifications of the arrangement herein described fall, of course, within the scope of my invention.

I claim:

35 1. An electrical amplifier circuit comprising, in combination, a vacuum tube device including an anode, a cathode, and a control electrode, an input circuit associated with said cathode and control electrode, a plate 40 coil connected to said anode, a second coil coupled to said plate coil, and connected in series therewith between said cathode and anode, and a balancing condenser connected

between said control electrode and the junction of said plate coil and said second coil, 45 whereby said amplifier circuit may be balanced to reduce retroaction.

2. An electrical amplifier circuit comprising, in combination, vacuum tube device including an anode, a cathode, and a control electrode, an input transformer having a secondary connected between said control electrode and said cathode, an output transformer having a primary connected at one terminal to said anode, a coil coupled to 50 said output transformer primary and connected between a second terminal thereof and said cathode, and a balancing condenser connected between said control electrode and the junction of said coil and said output transformer primary, whereby said amplifier circuit may be balanced to reduce 55 retroaction.

3. An electrical amplifier circuit comprising, in combination, a vacuum tube device including an anode, a cathode, a control electrode, and a fourth electrode, an input transformer having a secondary connected between said control electrode and said cathode, an output transformer having a primary connected at one terminal to said anode, a coil coupled to said output transformer primary and connected between a second terminal thereof and said cathode, a 65 balancing condenser connected between said control electrode and the junction of said coil and said output transformer primary, and means for imparting a positive potential to said fourth electrode with respect to 70 said cathode, whereby said amplifier circuit may be balanced to reduce retroaction while giving a relatively high amplification.

In testimony whereof, I affix my signature.

LEWIS M. HULL.
